N.J. & J.P. Wemmer Improved Branding Machine.

74263

FIG.1.

PATENTED
FEB 11 1868

FIG.3.

W.M.C.S.P.S. { Wm. B. Thomas
{ S. H. Godman.

United States Patent Office.

NELSON J. WEMMER AND JOHN P. WEMMER OF PHILADELPHIA, PENNSYLVANIA.

Letters Patent No. 74,263, dated February 11, 1868.

IMPROVEMENT IN BRANDING-INSTRUMENT.

The Schedule referred to in these Letters Patent and making part of the same.

TO ALL WHOM IT MAY CONCERN:

Be it known that we, NELSON J. WEMMER and JOHN P. WEMMER, of Philadelphia, Pennsylvania, have invented an Improved Branding-Machine; and we do hereby declare the following to be a full, clear, and exact description of the same.

Our invention consists of a branding-iron which is maintained constantly hot, in combination with devices fully described hereafter for holding the object to be branded, and pressing it against the iron.

In order to enable others to make and use our invention, we will now proceed to describe its construction and operation, reference being had to the accompanying drawing, which forms a part of this specification, and in which—

Figure 1 is a sectional elevation of my improved branding-machine.

Figure 2, a transverse section on the line 1-2, fig. 1, and

Figure 3, a sectional plan view on the line 3-4, fig. 1.

Similar letters refer to similar parts throughout the several views.

The frame of the instrument consists of a bed-plate, B, two uprights, A A, secured to the bed-plate, and two arms, C and D, secured to and projecting from the said uprights. Upon the bed-plate B rests a small gas-stove, E, or other suitable heating-apparatus, above which is secured, either permanently or so as to be detached, a branding-iron, F, the latter being so adjusted as to be quickly heated and maintained at the proper temperature. In the arm C, directly above the branding-iron, slides a rod, G, against a pin on which bears the forked end of a flat spring, H, secured at its opposite end to the arm C, the said spring tending to maintain a collar, e, on the rod against a projection, a, on the end of the arm C, as shown in fig. 1.

The rod G is operated by a cam-lever, J, which bears on the upper end of the rod, and turns on a pin, f, passing through the end of the arm D. At the lower end of the rod G is secured in any suitable manner a plate, K, which can be brought in contact with the upper surface of the branding-iron by depressing the rod, G.

A guide, L, consisting of an upper and lower plate, i and i', connected together at the rear by a block, j, is secured to each end of the block K, these guides being adjusted and being secured after adjustment by set-screws, k k, which pass through slots in the upper plates i i, and between each of the bottom plates i', and the under surface of the plate k, is a space sufficient for the introduction of the plate or board to be branded.

The branding-iron F is lettered or ornamented upon its upper face in the usual manner, and is heated until it will char any surface of wood that is brought in contact with it.

The cigar-box lid or other object to be branded is passed between the under surface of the block K and the plates i', in which position it is securely held, as shown in the drawing. Then the cam-lever J is operated, depressing the rod G and bringing the board in contact with the branding-iron F, where it is held for an instant until it receives the desired impression, (see fig. 2,) after which the cam-lever is turned back, permitting the rod G to rise, which it does by the action of the spring H.

If it be desired to duplicate the impression upon the board, the latter is pushed through the guides a short distance, and the operation repeated as before.

When a board of different size is to be branded, the set-screws k are loosened and the guides L shifted until the board, guided by the block j, is directly over the centre of the branding-iron, as shown in fig. 1.

A spiral spring encircling the rod G, and resting upon the arm C, may be used instead of the flat spring H, without departing from my invention.

In branding in the usual manner much time is lost in heating the iron, the operation is irregular, and the impressions more or less imperfect—objections which are obviated by the use of our invention, as the iron is stationary and is always maintained at the proper temperature.

We claim as our invention, and desire to secure by Letters Patent—

1. An adjustable holder, constructed for the reception and retention of a plate or other object to be branded, in combination with a stationary branding-iron, heated by the apparatus described, or its equivalent, all substantially as set forth.

2. The adjustable guides L L, in combination with the plate K, substantially as and for the purpose specified.

In testimony whereof, we have signed our names to this specification in the presence of two subscribing witnesses.

NELSON J. WEMMER,
JOHN P. WEMMER.
